UNITED STATES PATENT OFFICE.

JOHN S. MILLIN, OF PHILADELPHIA, PENNSYLVANIA.

DESIGN FOR A PILLOW-TOP.

51,733.

Specification for Design.

Patented Feb. 5, 1918.

Application filed May 5, 1917. Serial No. 166,756. Term of patent 3½ years.

To all whom it may concern:

Be it known that I, JOHN S. MILLIN, a citizen of the United States, residing in Philadelphia, Pennsylvania, have invented a certain new, original, and ornamental Design for an Article of Manufacture, of which the following is a specification, reference being had to the accompanying drawing, forming part thereof, in which the figure is a plan view of a pillow-top illustrating my new design.

I also contemplate using this design in the form of a banner, medal, badge, button, shield, flag, pennant, or emblem, and as patriotic insignia, and as a bureau scarf, table cover and similar articles, produced by any method or process of manufacture.

I claim:

The ornamental design for an article of manufacture, substantially as shown and described.

JOHN S. MILLIN.
